INDUCTION HEATING APPARATUS

James W. Peach, Arbutus, and Clarence A. Kuhne, Parkville, Md., assignors to Westinghouse Electric Corporation, East Pittsburgh, Pa., a corporation of Pennsylvania

Application April 18, 1957, Serial No. 653,594

7 Claims. (Cl. 219—10.49)

This invention relates to electric induction furnaces and more particularly to furnaces which can be used for heating billets, bars and similar workpieces to forging or extruding temperatures.

In the heating of workpieces for forging or extrusion by automated apparatus, the advantages of using electrical induction apparatus capable of heating the workpiece rapidly, successively and accurately to a predetermined temperature is well recognized. In induction coil billet heating apparatus it is usual to position the billet centrally of the induction coil and to shift the billet longitudinally through a tunnel formed by the convolutions of the induction coil. In order to keep the power factor of the induction coil reasonably near unity, it is desirable to keep the air gap between the workpiece and the convolutions of the induction coil as small as possible.

In conflict with the foregoing desideratum is the necessity of providing thermal and electrical insulation between the workpiece pathway and the convolutions of the induction coil. An accepted practice in the art has been to provide metal or ceramic liners of heat resistant material surrounding the workpiece pathway to protect the induction coils from heat radiated by the workpieces and from physical injury which might be caused by insertion or withdrawal of heavy workpieces from the coil. In addition to providing thermal and physical protection for the induction coil, the liner structure should be sufficiently strong, rigid and rugged to support the workpieces during the heating cycle.

It is further desirable in such furnaces to provide wear rails extending longitudinally inside the induction coil along which rails the workpieces may be shifted. At forging temperatures of about 2000° F. and above, workpiece supporting rails of known alloys have very little strength in bending so that even though rail supports are provided every few inches, heavy and thick rails are required to support the mass of the workpiece. The allowance of additional space for heavy rails necessitates an even greater air gap between the induction coil and the metal to be heated. The excessive air gap tends to result in low efficiency of the induction heating coil and a low power factor of the coil so that an excessive number of capacitors are required in order to correct the power factor to a predetermined figure.

In the heating of workpieces for forging, it is imperative that the workpieces be heated throughout to a relatively uniform temperature so that no cold areas or temperature differentials will exist between different portions of the heated workpiece. This requirement becomes increasingly important in automated apparatus wherein the heated workpiece is delivered to the forging presses almost immediately after being ejected from the induction heating furnace. In such apparatus the dwell time after heating, before the billet is delivered to the forging press, may be so short that temperature equalization of the different portions of the billet is not obtainable. Thus, it is necessary that the workpiece support surfaces or

2

rails within the induction furnace be adapted for operation at relatively high temperatures so that areas of a workpiece in contact therewith will not be unnecessarily cooled by conduction of heat to the workpiece support members.

Accordingly, it is an object of this invention to provide a furnace having improved workpiece supporting surfaces.

It is another object of the invention to provide a hollow liner for billet heating furnaces with elongated support rails carried within the liner for slidably supporting workpieces and with such rails being supported in a manner such that they are maintained at a first relatively high temperature while the members which support the rails are maintained at a second and relatively low temperature.

It is a further object of the invention to provide a workpiece supporting rail which is maintained at a first temperature and to provide a load supporting member for imparting strength and rigidity to the rail, with the latter member being maintained at a relatively low temperature and with the assembly having a high impedance to transverse heat flow between the workpiece contacting member and the load supporting member.

It is an additional object to provide an induction coil which is supported by an internally extending metallic liner member with the liner member having rail members positioned therein to be supported thereby and with the rail members being thermally insulated from the liner so as to be normally operative at a temperature appreciably higher than that of the liner member.

It is a different object of the invention to provide end support means for the coil liner for supporting the entire induction coil assembly including the workpieces supported within the coil liner.

It is still another object of the invention to provide an induction coil assembly constructed so as to permit removal and replacement of the workpiece supporting rails without disturbing the induction coils and the induction coil liner.

It is a still further object of the invention to provide an improved heat resistant workpiece supporting rail having a head portion along which workpieces may slide and having a strength imparting base portion parallel thereto with the head portion and the base portion being thermally insulated from each other so as to present a high impedance to transverse heat flow from workpieces supported thereon.

It is a still additional object of the invention to provide an induction heating coil having a plurality of longitudinally positioned workpiece support members which are thermally insulated from the induction coil so that the support members will conduct a limited amount of heat from the surface of a workpiece.

It is a still different object of the invention to provide a rigid, rugged and compact induction furnace chamber capable of supporting large and cumbersome billets or workpieces and operative to heat such workpieces uniformly to predetermined temperatures.

These and other objects of my invention will be apparent from the following description taken in accordance with the accompanying drawing throughout which like reference characters indicate like parts, which drawing forms a part of this application and in which:

Figure 1 is a longitudinal side view of an electrical induction heating furnace in accordance with the invention;

Fig. 2 is a sectional view taken along the lines II—II of Fig. 1 and illustrating the induction coil liner member and the workpiece supporting rails and insulating structure; and

Fig. 3 is a sectional view similar to that of Fig. 2,

showing a second embodiment of our invention and illustrating an alternative structural arrangement of the workpiece supporting rails and thermal insulating means.

In copending application Serial No. 630,367, filed December 24, 1956, and assigned to the assignee of the present application there is disclosed an induction furnace apparatus which is in many respects similar to the induction furnace of the present invention and which discloses a type of high speed production apparatus in which the present invention may be advantageously employed.

Referring now to the drawings, the induction heating apparatus as shown in Fig. 1 comprises a plurality of coil sections 10 formed of a single layer of a hollow rectangular electrical conductor 12 with said sections being arranged in end to end relationship so as to provide a workpiece pathway 14 or tunnel axially therethrough. The furnace coil assembly 16 is preferably mounted horizontally and longitudinally on top of an appropriate table or support frame (not shown) and is supported above the table surface by means of a pair of end plates 18 which are positioned at opposite ends of the end-to-end aligned sections 10. The end plates 18 are preferably of substantially rectangular configuration and are provided with substantially rectangular openings through which the ends of an induction coil liner member 20 project. The two end plate members 18 thus support each end of the liner member 20, and the convolutions 12 of the induction coil 10 are carried on and supported by the liner member 20 intermediately of the end plate members 18. The helical convolutions 12 of the induction coil 10 may be insulated from each other and from the coil liner member 20 by means of glass cloth sleeving and glass tape impregnated with a suitable high temperature varnish or other suitable insulation imposed between adjacent convolutions of the coil. The ends 22 of each section 10 of the induction coil are bent outwardly and may be provided with appropriate electrical connections and connections for a water cooling conduit for circulating a coolant through the convolutions 12 of the coil. The structural details of the induction coil convolutions, the electrical connections and water connections are essentially conventional and have been omitted from the drawing. The induction coil sections 10 preferably extend over the entire space between the end support plate members 18. In the form of the invention illustrated in Fig. 1, the inductor coil sections 10 are shown as being formed of a hollow rectangular conductive member although it is to be understood that the coil sections may be formed of circular tubing or of a hollow conductor having another form of cross section.

The coil liner member 20 on which the coil sections 10 are supported is preferably formed of a thin sheet of a tough, wear resistant, heat resistant and non-magnetic metal of relatively low electrical conductivity. The thin metal sheet is bent to form an elongated hollow substantially rectangular tube 20 having rounded corners and having external dimensions slightly larger than the internal dimensions of the inductor coils 10 with the internal dimensions of the liner member 20 being sufficiently larger than the external dimensions of the workpieces to be heated so as to accommodate appropriate insulation and specific workpiece supporting means to be hereafter described.

As shown in Fig. 2, the liner member 20 is split longitudinally at one point in its periphery so as to provide a longitudinally extending opening 24 which interrupts the peripheral continuity of the liner member 20. This interruption or longitudinal opening 24 in the liner member 20 is provided to prohibit the induction coils from inducing a circulating current in the liner member 20 which would reduce the efficiency of the apparatus and would tend to overheat the liner member 20.

The metal of which the liner member 20 is formed may be, for example, a high tensile strength stainless steel or nickel alloy steel having substantially non-magnetic properties so that the magnetic field induced by the induc-

tion coil will pass transversely through the coil liner member 20 to thread through the workpieces positioned in the workpiece pathway 14. The longitudinal opening 24 in the stainless steel liner member 20 may if so desired be sealed by means of two layers of asbestos sheet and appropriate clamping means (not shown) on opposite sides of the liner member 20 adjacent the longitudinal opening 24. Such sealing may be particularly desirable when the workpieces are to be heated in an inert atmosphere. With the sealing arrangement described and the imperforate coil liner member 20, the inert atmosphere may be substantially contained within the coil liner 20 thereby rendering it unnecessary to provide an additional enclosure for containing the inert atmosphere. In addition, the asbestos seal of the longitudinal opening 24 as described is operative to prevent hot gases and combustion products from the heated workpiece from contacting the induction coil insulation.

If so desired, the induction furnace assembly 16 may be provided with elongated tension members extending between the end plates for resiliently holding the coil sections in tightly pressed end to end alignment, thereby suppressing vibration of the coil sections. Alternatively, the coil sections may be held against vibration by spring loaded jack screws (not shown) used to force apart two flat washers of nonmagnetic material having external dimensions larger than the coil 10 and having inside dimensions slightly larger than the liner member. By forcing the washers longitudinally apart the coil sections 10 are compressed against the opposite end plates 18 and are thereby restrained against vibration and electromagnetic forces. The restraining washers are preferably split at one point adjacent the liner periphery to prohibit circulating currents from flowing in the washer.

As best shown in Fig. 2, the coil liner member 20 is positioned longitudinally within the aligned coil sections 10 and is equally spaced from the inner walls 26 of the coil convolutions. On the exterior of the coil liner member 20 there is provided a thin sheet 28 of thermally conductive metal which may be fastened to the coil liner member by means of conventional screw type fastening member. The thermally conductive sheet 28 carries on the outside thereof a plurality of fluid conduit members 30 which extend longitudinally of the coil liner and are interconnected at their ends so as to provide a serpentine path for a cooling fluid. The serpentine cooling fluid conduit 30 is provided to absorb heat which is conducted from the heated workpiece to the liner member 20 to thereby maintain the coil liner member 20 relatively cool so that it will have maximum strength for supporting the workpieces. In some applications of the present invention the coil liner 20 may be sufficiently cooled by means of the fluid cooled induction coil convolutions 12 in combination with appropriate thermal insulating material 32 positioned adjacent the inside of the coil liner member 20. In such cases the serpentine cooling fluid conduit 30 may be dispensed with so that the coil convolutions 10 may be carried closely adjacent the exterior of the coil liner member 20, thus providing a furnace in which the air gap between the coil sections 10 and the workpieces is minimized. Closely adjacent the inside of the coil liner member 20 there is provided the relatively thick layer 32 of thermal insulating material which may, for example, be a high temperature insulating material such as aluminum silicate felt. Inside the layer of thermal insulating material 32 there is provided an inner liner 34 of high temperature alloy material in the form of a thin sheet. This inner liner 34 is provided to hold the thermal insulating material 32 in place closely adjacent the liner member 20 and to protect the insulating material 32 from deterioration or damage caused by combustion products, scale or other extraneous material which may be introduced by the workpieces. The inner liner 34 is supported in position by short bolts 36 formed of heat resistant

75 material which extend through the inner liner 34, the

thermal insulating material 32 and are threaded into or otherwise attached to the coil liner member 20. The inner liner member 24 may if so desired be perforated or saw cut to prevent deformation thereof due to heat expansion. Alternatively the inner liner 34 may, if so desired, be formed of heat resistant wire screen or of short sections of heat resistant alloy with the construction in either case being designed to avoid bowing or deformation of the liner 34 when heated. At angularly spaced positions inside the inner liner 34 and contiguously adjacent the workpiece pathway 14 there are provided a plurality of longitudinally extending rail members 40 positioned and adapted to support workpieces in the workpiece pathway 14. The rail members 40 preferably extend continuously from one end of the furnace liner 20 to the other end and thereby provide a smooth and continuous surface along which the workpieces may be shifted or slid.

Between each rail member 40 and the inside of the liner member 20 there is provided a pair of spaced, longitudinally extending rods 42 for supporting the rail member 40 in parallel spaced relation to the liner member 20. The load supporting rods 42 may be held in position by appropriate lugs attached to the liner member 20 at spaced points therealong or may be otherwise fastened relative to the liner 20 so as to permit longitudinal expansion of the rods. The load supporting rods 42 are effective to rigidly support the rail member 40 along its full length so that the rail member 40 will not tend to be deflected or bent by heavy loads positioned thereon when the rail member is heated to temperatures approaching the workpiece temperatures. At forging temperatures of about 2000° F. and above, workpiece supporting rail members of known heat resistant alloys have very little strength in bending so that even though separate rail support pillars were provided every few inches, a heavy rail of undesirable thickness would be required to adequately support the load. Furthermore, use of the insulating material 32 as the sole supporting means for the rails is generally inadequate in that heavy billets will tend to compress the insulating felt 32 after a short period of use, thereby reducing the insulating effect and necessitating complete dismantling of the heating furnace for replacement of the thermal insulating material.

As shown in Fig. 2, the rail members may be located in position by a removable attachment to the inner liner member 34. The rail 40 is bolted at the infeed end to prevent movement with the billets, and is laterally positioned by lugs welded to the inner liner at spaced positions therealong. The weight of the rail members 40 and the workpiece positioned thereon is supported by the cylindrical rods 42 which are positioned between the rails 40 and the coil liner member 20. The cylindrical load supporting rods 42 preferably extend the full length of the induction heating furnace 16 so that the rail 40 is supported by the rods 42 at all points along its full length with the load-carrying rods 42 in turn being supported by the coil liner member 20. By virtue of the heretofore described rail support construction, it is possible to employ a work supporting rail member 40 having a relatively small thickness as compared to its width. The use of such a thin rail is a distinct advantage in that thicker rails have a tendency to bow or deform due to temperature differential between the inside and outside surfaces of the rail. Experimentation has shown that excessively thick rails tend to fracture after extended periods of use because of the thermal stresses created within such thicker rails. In addition, the use of the thin work supporting rail members 40 as heretofore described permits a much smaller distance between the workpiece and the coil turns 12 thus permitting a much smaller air gap. The workpiece supporting assembly formed by the rail member 40, inner liner 34 and support rods 42 is not permanently joined to the coil liner member 20. Rather, each rail assembly is releasably secured to the liner member by

flat headed bolts of heat resistant material which extend through the rail, through appropriate openings in insulating material 32, and are threaded into or otherwise fastened to the liner member 20 so as to maintain the rail members 42 in resiliently pressed tangential engagement with the liner member 20. By use of this releasable attachment of the rail assemblies within the furnace a system is provided in which any one of the rail assemblies may be individually removed from the furnace without disturbing the liner member 20 or the insulating material 32. This enables replacement of any worn or damaged rail member simply by removing the bolts which independently connect it to the liner member 20.

In Fig. 3 there is shown an alternative structural arrangement in which a compound rail structure 44 includes a channel member 48, a layer of thermal insulating material 50 and a work supporting rail member 40. In the apparatus of Fig. 3 the induction coil sections 10, the coil liner member 20, the thermal insulating material 32 and the inner liner 34 are essentially similar to those same components as shown in Fig. 2 and are, therefore, designated by the same numerals as in Fig. 2. In Fig. 3 the load supporting rod members 46 comprise longitudinally extending hollow tubular members which may be provided with appropriate end connections for circulation of a cooling fluid therethrough. The load supporting tubes 46 may be attached to the liner member 20 by bolts or by appropriate clamps threading into or otherwise making positive attachment to liner member 20. On the interior side of the load supporting tubes there is provided a longitudinally extending channel member 48 formed of heat resistant alloy and attached to the load supporting tubes 46 by welding at spaced positions therealong. The channel member 48 is formed and adapted to retain within its channel a ceramic or firebrick thermal insulating material 50 which extends longitudinally from end to end of the channel member 48. The workpiece contacting rail members 40 are similar to the rail members 40 as shown and described with reference to Fig. 2. The rail members 40 provide a longitudinally extending, smooth and continuous surface along which workpieces may be shifted. The rail member 40 may be secured to the channel member 48 by means of appropriate flat headed bolts (not shown) extending through the rail 40, through the thermal insulating material 32 and threaded into or otherwise fastened to the liner member 20. By using the weight carrying metal liner 20 and the relatively thin compound rail members 44 the inevitable air gap between the coil and workpieces can be made appreciably smaller than that of prior art furnaces. Likewise, reduction of the spacing between the workpieces and the induction heating coils 10 affords a more compact furnace than that of prior art induction heating apparatus. By providing the thermal insulating material 50 between each channel member 48 and each rail member 40, a compound rail structure 44 is provided which has a high impedance to transverse heat flow from the rail member 40 to the relatively cold liner member 20. By means of the unique rail structure of the invention, the coil liner member 20 is maintained relatively cool for maximum strength, thereby enabling it to be employed as a load carrying member and thus eliminating the necessity of providing support members extending through the coil liner 20 and between convolutions of the induction coil as has been common in the prior art.

Throughout the specification the term "induction heating coil" has been used to apply to the electromagnetic inducing element relative to which the workpiece is positioned to be heated by electromagnetic induction. The term "heating coil" is to be broadly construed to include electromagnetic inductor devices of all types regardless of whether the inductor coil assembly is substantially circular in cross section or is substantially rectangular in cross section or is of some other shape and dimension. The term "rail" is to be construed as meaning any in-

tegral or sectionalized surface on which a billet or the like may slide. Likewise, whereas the invention has been shown and described as relating to an apparatus for heating substantially rectangular workpieces, it is to be understood that it is equally applicable to similar apparatus for heating cylindrical workpieces or workpieces having other special cross-sectional configurations.

While the present invention has been shown in one form only, it will be obvious to those skilled in the art that it is not so limited but is susceptible of various other changes and modifications without departing from the spirit and scope thereof.

We claim as our invention:

1. An induction heating apparatus comprising an induction coil having a workpiece pathway extending longitudinally therethrough, a liner member for said coil comprising a thin-walled metal tube of interrupted circumferential continuity, means for supporting said liner member adjacent each end thereof with said coil being externally supported by said liner member, a plurality of work supporting rails angularly spaced and longitudinally extending within said liner member adjacent said pathway, and a plurality of rail support members positioned between said rails and said liner member so as to rigidly support said rails with said rails being thermally insulated from said liner member so as to substantially restrict the flow of heat from said rails to said liner member.

2. An induction heating apparatus comprising an induction coil having a workpiece pathway extending longitudinally therethrough, a liner member for said coil comprising a thin-walled metal tube of interrupted circumferential continuity, means for supporting said liner member adjacent each end thereof with said coil being externally supported by said liner member, a plurality of work supporting rails angularly spaced and longitudinally extending within said liner member adjacent said pathway, a plurality of rail support members positioned between said rails and said liner member so as to rigidly support said rails with said rails being thermally insulated from said liner member so as to substantially restrict the flow of heat from said rails to said liner member, and means for cooling said liner member so that said liner member may be maintained at a temperature at which it retains substantial mechanical rigidity.

3. In apparatus for induction heating having a longitudinally extending workpiece pathway, a thin-walled metal tubular member of interrupted circumferential continuity surrounding said pathway, means for supporting said member adjacent the ends thereof, an induction coil comprising a plurality of convolutions of electrical conductor supported on the outside of said tubular member, a plurality of longitudinally continuous workpiece supporting rails supported contiguous to said pathway by said tubular member, each of said rails comprising a facing member along which workpieces may be slid, a load supporting member adapted to be positioned longitudinally adjacent the inside of said tubular member, and thermal insulating means disposed between said facing member and said load supporting member so as to

substantially resist the flow of heat from said workpieces to said load supporting member.

4. An induction heating coil having longitudinal work supporting rails within the coil, a thin walled metallic liner member positioned between said coil and said rails for supporting the same, fluid conduit means thermally associated with said liner member for cooling the same, and elongated rail support members positioned in parallel adjacency between said rails and said liner member to support said rails, with said rails and rail support members being connected to said liner so as to have a high impedance to transverse heat flow whereby said supports conduct a relatively small amount of heat from said rails and the heated surface of a workpiece contiguous to said rails.

5. An electric heating furnace comprising an induction heating coil, workpiece guide rails within said coil, a thin-walled metal liner member outside the rails within the coil, a plurality of elongated rail support members positioned longitudinally of said coil between said rails and said liner member so as to support said rails in parallel spaced relation to said liner member, with said support members being formed of a material of low heat conductivity and having a small contact area with said liner member so as to provide a high impedance to heat flow from said rails to said liner member.

6. An induction furnace a substantially tubular heating coil, a thin-walled liner member of interrupted circumferential continuity within and adjacent said coil, means at the ends only of said liner member for supporting same, heat resistant longitudinally continuous metal rails positioned within and spaced from said liner member, and rail support members longitudinally positioned within said coil between each of said rails and said liner member, said rail support members being in the form of substantially cylindrical rods and being adapted to tangentially engage both said liner member and said rails to provide a heat conduction path therebetween, with said path having a substantially reduced cross-sectional area portion.

7. An induction heating apparatus comprising a heating coil, an elongated hollow liner member longitudinally positioned within said coil and supporting said coil, a plurality of longitudinally and angularly spaced support members within said liner member, releasable means for attaching said members to the interior of said liner member, a plurality of longitudinally continuous workpiece contacting rails secured to said support members, with each of said rails and its associated support members comprising a workpiece supporting assembly independently removable from said liner member upon release of said releasable means.
